UNITED STATES PATENT OFFICE.

PERCY BERESFORD WRIGHT KERSHAW, OF LONDON, ENGLAND, ASSIGNOR TO OWEN DAVID LUCAS, OF LONDON, ENGLAND.

CARBURETER AND LIKE DEVICE FOR MIXING GAS OR VAPOR AND AIR.

No. 930,483.

Specification of Letters Patent. Patented Aug. 10, 1909.

Application filed April 6, 1908. Serial No. 810,360.

To all whom it may concern:

Be it known that I, PERCY BERESFORD WRIGHT KERSHAW, a subject of His Majesty the King of Great Britain, residing at London, in the Kingdom of England, have invented certain new and useful Improvements in Carbureters and Like Devices for Mixing Gas or Vapor and Air, of which the following is a specification.

10 My said invention has reference to carbureters and like devices for mixing gas or vapor and air, and is especially applicable to internal combustion engines, the main object of the invention being to provide a simple, compact and inexpensive contrivance for enabling an intimate and correctly proportioned and regulated mixture of such fluids to be supplied to the cylinders of an engine or other point of consumption.

20 In order that my invention may be clearly understood and readily carried into effect it will now be described more fully with reference to the accompanying drawings, in which:—

25 Figure 1 is an elevation of a carbureter embodying the features of the invention; Fig. 2 is a longitudinal section taken approximately on the line 2—2 of Fig. 1; Fig. 3 is a transverse section, taken approximately on the line 3—3 of Fig. 2; Fig. 4 is a face view of one of the disks employed; Fig. 5 is a face view of the other disk; Fig. 6 is a section of disks of a somewhat modified form; and Fig. 7 is a face view of one of the said modified 35 disks. Fig. 2^a is a view on an enlarged scale showing particularly the means for rotating the disks and for controlling the valve of the fuel supply.

30 *a* is a mixing chamber or casing, *b*' a supply pipe forming one part of the supply passage leading thereto, and *c* the rotary part of said supply passage constituting a hollow shaft; *d*, *e* are centrifugal disks mounted on said hollow shaft; *f* is a fan; *g* is a valve for automatically controlling the supply of fluid, and *h* a hand-controlled throttle valve.

35 The mixing chamber *a* is open at both ends and is provided with two spiders *a'* and *a''* adapted to support the pivots or bearings on 40 which the rotary parts of the carbureter turn. One of such bearings comprises a

nozzle *b* forming a continuation of the vapor supply pipe *b'*, said nozzle extending into the interior of the casing *a* where it terminates in a point *b*². The hollow shaft *c* has at one end 55 a concave face which fits over the point *b*² of the nozzle so as to be capable of freely rotating thereon, while its other end is secured fast to the disk *d*.

40 The centrifugal disks *d*, *e* have their adjacent faces closely in contact with each other, and are secured firmly together by screws or the like. Recesses *d*', *e*' in the inner faces of both these disks register with each other to form a central cavity from which 55 extend the curved helical grooves *d*². Such grooves consist of mere scratches in the face of the disk *d* and are preferably of approximately the form shown in Fig. 4. The other disk *e* has on its side remote from the 60 disk *d* a recessed boss *e*², into which penetrates a pin *a*³ carried by the spider *a*² and constituting the other bearing above referred to. Between the peripheries of the 65 said disks and the casing *a* is an annular interspace *a*⁴ of liberal capacity through which the air, drawn in through the open outer end *a*⁵ of the casing, passes to the cylinders of the 70 engine by way of the aspirator tube *a*⁶ which is secured to the engine by means of a flange 75 *a*⁷ and bolts *a*⁸.

75 It will be seen that as the disks are rapidly rotated, the hydro-carbon fluid which flows by way of the tubular shaft into the central space between the disks, will be thrown outward by centrifugal force and will emerge 80 from between the peripheries of the disks in the form of a ring or corona of mist or of exceedingly fine spray which will be cut at every point by the air current traveling in a 85 direction parallel with the tubular shaft, and will thus become intimately mixed with said air current and carried along therewith. The current of air, before reaching the disks, passes through and over the fan *f* and rotates the same for the double purpose of imparting the requisite rotary motion to the 90 disks and of actuating the automatic valve *g* which controls a central aperture *d*³ in the disks *d*. Said fan is mounted fast on the 95 hollow shaft *c* through the intervention of a sliding sleeve *f'* whose position on the shaft 100

is controlled by a spring f^2 . Rods g', g' passing loosely through apertures in the disk d connect the fan with the valve g , the arrangement being such that the air draft, induced by the stroke of the piston upon the vanes of the fan will, besides rotating the latter, cause said fan to slide in opposition to the resistance of its spring toward the disk d and will thereby open the valve g through the intervention of the connecting rods g' . At the end of the suction stroke, however, the spring will force the fan in the opposite direction, and will thereby close the valve g . This valve would usually only be required in the case of engines in which there is an appreciable interval of time between the suction strokes.

The throttle valve h , which is normally held open by a spring h' , is provided with means (not shown) of any suitable kind, for enabling it to be partially or entirely closed, either by hand or automatically, whenever desired.

The invention is not confined to the precise details of construction above described and shown, which may be varied in a number of ways without departing from the nature of the invention. For instance, in place of arranging the fan f on the side of the disks d, e remote from the cylinders, as shown, it may obviously be located on the side thereof nearest to the cylinders, as for example within the aspirator tube a^6 . Moreover, where the carbureter is used in connection with an engine having more than one working cylinder, the valve g may in some cases be dispensed with. Furthermore, the centrifugal disks may be constructed in the manner shown in Figs. 6 and 7, instead of that exemplified in Fig. 2. In said Figs. 6 and 7 the hollow shaft c is dispensed with and the disk d has a prolonged boss d^4 which engages directly with the nipple b . The four screws shown in Fig. 3 for connecting the two disks together are also dispensed with, and in lieu thereof a single central screw d^6 is employed for the same purpose, said screw engaging with an internal flange d^6 in the boss d^4 and with the disk e . A number of holes d^7 in the flange d^6 permit of the passage therethrough of the hydro-carbon. An advantage of this arrangement is that space in the groove part of the disk need not be taken up by screws, and therefore the whole face of the disk can be grooved, as in Fig. 4.

The fan f may be provided with any suitable means (not shown) for enabling the pitch of its vanes to be adjusted as desired. Moreover said fan may be replaced or supplemented by a mechanical device connected with some moving part of the engine for rotating the disk; or other means may be employed.

One of the advantages attained by the above described invention is that the float chamber heretofore found necessary may be dispensed with.

What I claim and desire to secure by Letters Patent of the United States is:—

1. A carbureter comprising a mixing chamber, a rotary disk having capillary passages extending from the center of the disk to the periphery thereof, means for supplying hydro-carbon to the said passages, an air supply for the mixing chamber, and means for rotating the disk to cause the hydro-carbon to be thrown centrifugally from the periphery thereof.

2. A carbureter comprising a mixing chamber to which air is admitted, a rotary disk provided with capillary grooves extending from its center to its periphery, means for supplying hydro-carbon to the center of the disk, and means for rotating the disk whereby the hydro-carbon is thrown from the periphery thereof in a finely divided condition and mixed with the air supplied to the mixing chamber.

3. A carbureter comprising a mixing chamber, a rotary disk mounted therein provided with grooves extending from its center to the periphery, means for supplying hydro-carbon to the center of the disk, means for conveying air through the mixing chamber and a fan in the path of the air, operatively connected with the disk and rotated by the air current, whereby the hydro-carbon is thrown centrifugally from the periphery of the disk.

4. A carbureter comprising a mixing chamber through which air is drawn or forced, disks secured to each other and having a space between them for the passage of fuel, means for feeding fuel between the disks and means for rotating the disks to cause the fuel to pass to the mixing chamber centrifugally in the form of a mist or fine spray in the path of the air passing through the chamber.

5. A carbureter comprising a mixing chamber through which air is drawn or forced, rotary disks having between them grooves through which hydro-carbon is supplied, means for feeding hydro-carbon to said grooves and means for rotating the disks to cause the hydro-carbon to be thrown centrifugally into the path of the air passing through the mixing chamber.

6. A carbureter comprising a mixing chamber through which air is drawn or forced, a rotary disk to which fuel is supplied and which acts centrifugally to throw hydro-carbon into the path of the air passing through the mixing chamber and a fan operatively connected with the disk and actuated by air passing through the chamber.

7. A carburetor comprising a mixing

chamber through which air is drawn or forced, a disk provided with grooves extending from its center to its periphery, means for supplying fuel to the central portion of the disk, a valve controlling the supply of fuel and a fan operatively connected to the valve and disk to rotate the disk and to actuate the valve.

In testimony whereof I have hereunto set my hand in presence of two subscribing witnesses this 28th day of March 1906.

PERCY BERESFORD WRIGHT KERSHAW.
